UNITED STATES PATENT OFFICE.

JOSEPH S. BURKETT, OF MACON, GEORGIA.

COLLAPSIBLE DERRICK.

Application filed July 28, 1925. Serial No. 46,619.

To all whom it may concern:

Be it known that I, JOSEPH S. BURKETT, a citizen of the United States, residing at Macon, in the county of Bibb and State of

5 Georgia, have invented certain new and useful Improvements in Collapsible Derricks; and I do hereby declare the following to be a full, clear, and exact description of the invention, such as will enable others skilled 10 in the art to which it appertains to make and use the same.

This invention relates to excavating and loading devices or apparatus and more particularly to a collapsible derrick or dumping 15 structure.

The principal object of the invention is to provide an improved apparatus or structure of the character referred to which may quickly be "set-up" in operative position and 20 "knocked down" intact for expedient removal from one location to another.

A practicable structure or form of apparatus embodying the invention is illustrated in the accompanying drawings which are to be 25 taken as a part of this specification.

In said drawings:

Fig. 1 is a plan view of the collapsible structure with parts arranged in operative position;

30 Fig. 2 is a side elevation of the same;

Fig. 3 is a plan view of the structure when collapsed or "knocked-down" and ready for removal to a new location; and

35 Fig. 4 is a side elevation of the folded structure shown in Fig. 3.

Referring to said drawings, 5 denotes a platform or supporting frame shown mounted at its rear end on wheels 6 and provided at its forward end with a yoke member 40 pivotally fastened to the rear end of an ordinary tractor 7 by means of a king-bolt 8, said platform or frame being thus mounted or supported on wheels and adapted to be drawn by the tractor in "trailer" fashion.

45 An A-type derrick 9 is shown supported and braced on the rear end of the platform 5, additional ties or brace-rods with turn-buckles (not shown) being advantageously employed to rigidly secure the same in place and idling pulleys 10 and 11 are shown provided in the upper end of said derrick for a purpose which will hereinafter appear.

50 Horizontally extended from the upper end of the derrick 9 is shown a yoke or boom member 9^a carrying an idling pulley 10^a at its outer extremity, said yoke or boom

member being adequately supported in position by means of brace or strut members 9^b bolted or otherwise secured to the derrick and its supporting frame as shown. 60

Cable drums 12 and 13 with shaft ends or journals supported in suitable bearings are shown provided on the forward end of the platform, said drums being driven by intermeshing gears 14 and 15 having associated 65 pawl and ratchet or other engageable means (not shown) with the drum shafts by which either or both may be released to idle against their respective drums for controlling the latter in a manner well known in 70 the hoisting-machine art. Suitable brakes (not shown), are also provided for each of said drums for holding the latter against rotation in either direction in a manner common to cable-reeling devices. 75

In the present instance, the actuating power for the drums 12 and 13, is imparted by the tractor motor to a shaft 16 through a sprocket chain 17, a driving pinion or gear 18 being keyed on said shaft in engagement 80 with the gear 15. By this means, rotation of the drums 12 and 13 may be independently or simultaneously effected in either direction, depending upon the direction in which the shaft 16 is caused to rotate. 85

Spaced skid-members 19 are shown with ends pivotally secured to the top of the derrick 9 and opposite ends pivotally connected to the upper extremity of an inclined platform 20 at either side thereof, said platform 90 in this instance being taperingly formed of sheet metal with countersunk rivets and converging lateral flanges or guides. Hooks 21 and eye-bolts 22 are also provided on either side of the platform for a purpose which will 95 hereinafter appear.

Swinging props or stanchions 23 are shown with ends swiveled to the upper end of said platform for normally supporting the latter in position as illustrated, and a 100 roller 24 over which a scraper or scoop is drawn to tilt and dump its load between the lateral skids 19, is shown supported in bearings at the lower ends of said skids.

A scraper 25 having lateral arms or trunnion-like extensions 26 by which it is supported upon the skid-members 19 when overbalanced or tilted to dump therebetween, may be drawn alternately in forward and rearward directions by means of hauling 105 and backing cables 27 and 28 respectively. The hauling-cable 27 is shown passing over

the pulley 11 with one end secured to and wound upon the drum 12 and its other end connected to the forward end of the scraper by means of a yoke-chain, while the backing-cable 28 is shown passing over the pulleys 10 and 10^a with one end secured to and wound upon the drum 13 and its other end connected to the rear end of the scraper by similar means after passing extensibly through snubbing-blocks 29 temporarily fixed at distant points in the field or area under excavation by means of anchors 30.

In the present instance, the scraper is drawn rearwardly to loading position by the cable 28 as it is wound upon its drum 13, the drum 12 being co-incidently allowed to run free so as to spend the cable 27 as the scraper is drawn to the desired point for loading. The scraper is then drawn forwardly to load and haul over the ground and up the inclined platform 20 to dumping position between the skids 19, by means of the cable 27 as it is wound upon its drum 12, the drum 13 being simultaneously allowed to run free so as to spend the cable 28 as the scraper is drawn forwardly. The specific details of operation and the various possible arrangements and methods of using the apparatus in different excavating and grading projects will be readily understood by those familiar with devices of the same general character, so that further description with respect thereto is considered unnecessary.

When it is desired to move the apparatus or structure to a new location, the scraper 25 is drawn forwardly by means of the cable 27 onto the platform 20 to the position shown in Fig. 3, whereupon the end 40 of said cable is disconnected from the scraper and secured by suitable means to the eye-bolts 22 at the lower end of the platform as shown in Figs. 3 and 4. In some instances it may be desirable to fasten or secure the scraper in place on the platform to prevent dislodgment, although it would not ordinarily be necessary. The anchors 30 with attached snubbing-blocks 29 are then uprooted and carried or else 45 drawn forwardly by the cable 28 winding on its drum to a position on the platform adjacent the scraper where they may advantageously be secured against displacement, the free end of said cable being then 50 disconnected from the rear of the scraper and secured by suitable means (not shown) to the elevated end of said platform. In this connection it may be stated that while it is generally unnecessary to withdrawn the free 55 end of cable 28 through the snubbing-blocks 29, it may in some instances be desirable so to do in order to save power and avoid undue strain upon the derrick and cable when the latter is reeled upon its drum 60 to raise the upper end of the platform 65

from folded position against the base of the scaffold. In Figs. 3 and 4 the cable 28 is shown with the snubbing-blocks and anchors removed, allowing the same to be drawn taut between the pulley 10^a at the 70 end of the boom 9^a and the top end of the platform without sagging from intermediate weights.

The props or stanchions 23 are next swung and secured by the hooks 21 in the position shown in Fig. 4, thus removing the support for the upper end of the platform. Should the props be difficult thus to move, the cable 28 which in the manner stated has been attached to the upper end of the 75 platform, may advantageously be reeled upon its drum sufficiently to raise said end slightly and relieve its weight from said props so that the latter may with ease be swung to such folded position. The tractor is then reversed while the drum 13 is allowed slowly to spend its cable 28, allowing the skid-members 19 to swing downwardly to the position shown in Fig. 4, thus bringing the upper end of the platform to folded position against the bottom of the derrick, after which the rocking pawl is set or the brakes are applied to said drum to prevent further rotation. The cable 27 is then reeled upon its drum 12 to elevate the lower end of the platform (to which it has been attached as stated) either to an upright position or to an angular position such as shown in Fig. 4, whereupon said drum is locked and 100 its brakes are applied to prevent the platform from lowering or dropping by reason of its weight. The entire apparatus thus compactly folded or collapsed may expediently be drawn by the tractor to a new location and again quickly placed in operative position.

In order to set-up the derrick and arrange the apparatus in operative position, the brakes on drum 12 are first gradually 110 released, allowing the platform to be lowered with its bottom end resting in the desired position on the ground, after which the cable 27 is disconnected from the eye-bolts 22 and again connected to the forward end of the scraper. The drum 13 is then actuated to wind the cable 28 thereon while the tractor is moved slightly forward, thus elevating the upper end of the platform sufficiently for the props or 115 stanchions 23 to be released and swung to the upright supporting position shown in Fig. 2, whereupon said cable is allowed to spend freely as it is drawn to a predetermined point in the field or area to be 120 excavated, said cable being again properly extended or passed through the snubbing-blocks 29, which are secured by their anchors 30 at respectively designated points, and returned with its free end again con- 125 130

nected to the rear of the scraper. The derrick is thus expediently placed in operative position and the apparatus is ready for use.

5 Obviously the present invention is not limited to the specific details of construction, arrangement of parts or modes of operation herein respectively shown and described, since various modifications to meet 10 different requirements and conditions may be made without departing from the spirit and scope of the invention.

Having thus described my invention, what I claim as new and desire to secure by 15 Letters Patent of the United States is:

1. A collapsible excavating and dumping apparatus comprising a power-drawn platform or frame; a derrick mounted thereon; an inclined platform adjacent to and lowerable against said derrick; skid-members pivotally connecting the derrick and the upper end of said inclined platform; swinging stanchions secured to and foldable against the last named platform and adapted normally to support the latter in inclined position; a scraper; hauling and backing cables for alternately moving the scraper in opposite directions and connectible to said inclined platform for raising and lowering the latter; pulleys on said derrick over which the cables are passed; and means on said first named platform by which the cables are controlled.

2. A collapsible excavating and dumping device comprising a tractor; a platform connected thereto in "trailer" fashion; a derrick mounted on said platform; an inclined platform adjacent to and foldable against said derrick upon said first named platform; skid-members pivotally connecting the upper ends of said derrick and said last named

platform and forming an extension of the latter; swinging stanchions secured to and foldable against the inclined platform adapted normally to support the latter in 45 inclined position; a scraper; cables for alternately drawing said scraper in forward and rearward directions and connectible to said inclined platform for raising and lowering the latter to and from normally inclined position; pulleys on said derrick over which said cables are passed; and controllable means on said first named platform for operatively reeling and spending the cables.

3. An excavating and dumping apparatus 55 comprising a tractor; a platform connected in "trailer" fashion to said tractor; a derrick mounted on said platform; a boom member extending from the upper end of the latter; an inclined platform adjacent to 60 and connected with said derrick and lowerable against the latter in collapsible position; skid-members extending from and pivotally connecting said inclined platform to said derrick adapted to fold against the latter; stanchions pivotally secured to and foldable against the inclined platform for normally supporting the latter in inclined position; a scraper movable up and down the incline adapted to dump loads between 65 70 said skid-members; hauling and backing cables for drawing the scraper in forward and rearward directions and connectible to said inclined platform for raising and lowering the latter to folded and operative positions respectively; pulleys on said derrick and on said boom member over which the respective cables are passed; and controllable means for operatively reeling and 75 80 spending the cables.

In testimony whereof I affix my signature.
JOSEPH S. BURKETT.
